(21) Appl. No.: **29/226,855**

(57) **CLAIM**

(22) Filed: **Apr. 1, 2005**

The ornamental design for a modular cylindrical dental case system, as shown and described.

(51) **LOC (8) Cl.** 03-01

DESCRIPTION

(52) **U.S. Cl.** D3/203.7

FIG. 1 is an exploded perspective view of a modular cylindrical dental case system showing our new design;

(58) **Field of Classification Search** D3/203.7, D3/201, 203.1, 203.2, 203.3, 203.4, 203.5, D3/203.6, 205, 294; D9/737, 624; 206/205, 206/368, 83, 361, 362.2; D10/40-44; D24/227

FIG. 3 is a top view thereof;

See application file for complete search history.

FIG. 4 is a bottom view thereof;
